Public Law 619, August 23, 1954
Patent expires October 1, 1968

7 Claims. (Cl. 292—83)

The present invention relates to improvements in door locks, particularly of the type adapted for use in automobiles.

It is an object of the present invention to provide a door lock of a very simple and inexpensive construction and requiring as few parts as possible.

Another object of the present invention is to provide a door lock which excels by being very easily assembled, by operating very safely and effectively, and by being of a very compact design, requiring little space.

A further object of the invention is to provide a door lock which may be used without change of construction for either left-hand or right-hand doors.

One essential feature of the invention for accomplishing the aforesaid objects consists in forming the latch member of the lock of a single leaf spring, either by bending said spring so as also to form the latch member, or by securing a separate latch portion on said leaf spring.

Further objects, features, and advantages of the present invention will be apparent from the following detailed description thereof as well as from the accompanying drawings, in which

Fig. 1 shows a perspective view of a door lock according to the invention in the locking position and adapted to be operated by a door handle;

Fig. 2 shows the door lock according to Fig. 1 in a longitudinal section, and it also shows a side view of the moveable parts of the lock in the open position;

Fig. 3 shows a cross section through the spring bolt of the lock according to the invention, taken along line 3—3 of Fig. 2; while

Fig. 4 shows a detail view of a reinforced spring bolt to be applied in place of the one shown in Figs. 1 to 3.

Referring to the drawings, the lock according to the invention consists of a housing having a front plate 2 with a cutout portion 3 therein, for example, of rectangular shape. A stationary stop member 4 is rigidly mounted in the side walls 1 of the housing at a point slightly below and behind the cutout 3, and a leaf spring 5 of a particular configuration is mounted on the inside of the front plate 2 near the upper end of the lock housing. At the level of the cut-out 3, leaf spring 5 is provided with an outwardly or forwardly curved portion 5a which may be, for example, of substantially semicircular shape. At the lower end of the curved portion 5a, leaf spring 5 extends for a short distance 5b in a straight direction and is then bent back nearly at a right angle so as to form a straight end portion 5c which extends substantially parallel to the main upper portion 5 and normally at a certain distance from the stop member 4. Below the straight portion 5c and in front of the end portion 5c, a sprocket member 6 having the noses 7 and 8 thereon is rotatably mounted in suitable apertures in the side walls 1 of the housing.

The function and operation of the lock as above described is as follows:

When in the locking condition, the moveable parts of

2

the lock assume the position as illustrated in Figs. 1 and 2. The leaf spring 5 normally presses with a slight initial tension against the inner wall of the front plate 2 of the housing, and the curved portion 5a projects through the cutout 3 so as to form a latch which is adapted to engage in the catch 10 of the notched bar 11 which is mounted in the door frame. The angular end portion 5c rests against the nose 7 of the sprocket member 6 and maintains the same in such an angular position that the stop nose 8 will abut against the inner wall of the front plate 2. With the sprocket 6 in this position, the square hole 9 will be disposed so that the door handles 12 when inserted therein will be in a substantially horizontal position.

When one of the door handles 12 is depressed, the nose 7 of the sprocket member 6 bends the leaf spring 5 into the position shown in Fig. 2, so that the latch portion 5a will be forced toward the left and out of engagement with the catch 10.

Rather than operating the lock by means of door handles 12 and the sprocket 6, the leaf spring 5 may also be actuated directly by a key, or a safety lock may be installed in the sprocket 6. Also, the leaf spring 5 may be made substantially straight up to the angular portion 5b, and the latch portion may be formed by a block member 13, as shown in Fig. 4, which is secured to the leaf spring 5 at the point of the cutout 3 in the front plate 2 of the lock housing.

While either the curved latch portion 5a or the block member 13 on the leaf spring 5 are provided with an inclined surface 14 so as to form a snap lock, the lock according to the invention may also be used, for example, as a lock for a drawer or the like, in which case the lock may, if desired, be installed in a horizontal position so that the leaf spring will then move either upwardly or downwardly. Also, if desired, the latch portion 5a may then be made straight rather than inclined.

Although my invention has been illustrated and described with reference to the preferred embodiments thereof, I wish to have it understood that it is in no way limited to the details of such embodiments or to the specific examples described, but is capable of numerous modifications within the scope of the appended claims.

Having thus fully disclosed my invention, what I claim is:

1. A door lock comprising a support including a front plate, a leaf spring member mounted on the inside and near one end of said front plate and having a main portion integral therewith adapted for resilient movement relative to said end, said main portion including an upper spring portion and a bent portion adjacent thereto and adjacent the middle of said main portion, said bent portion overhanging one end of said main portion, said bent portion forming a latch portion adapted to lock the door, said front plate having an actuating member adjacent said one end for positively moving said one end and thereby moving said main portion for positively moving said main portion from a closing position of said latch portion to an opening position thereof, and for releasing said main portion so as to enable movement of said latch portion to the closing position by the resilience of said leaf spring member, said front plate having an upper closure portion extending over said upper spring portion, said front plate further having a lower closure portion extending over said actuating member, said upper closure portion and said lower closure portion having spaced parts providing an aperture through which said latch portion projects.

2. A door lock as defined in claim 1, said support comprising a housing, the other end of said leaf spring member being mounted on said inside and near said one end of said front plate within said housing at a point spaced from said aperture, said spring member extending in a

longitudinal direction along said front plate and over and beyond said aperture, said actuating member being disposed within said housing at a portion of said housing opposite to the mounting of said other end of said spring member so as to cooperate with said one end of said spring member.

3. A door lock as defined in claim 2, wherein said one end of said main portion further includes an extension of said bent portion, said extension extending from said bent portion into said housing, said one end further including an offset portion extending from said extension, said actuating member being disposed at a point intermediate said offset portion and said front plate of said housing for cooperation with said offset portion.

4. A door lock comprising a support including a front plate, a leaf spring member mounted on the inside and near one end of said front plate and having a main portion adapted for resilient movement relative to said end, said main portion including a latch portion adapted to lock the door, said latch portion being inclined transversely to the length of said leaf spring member, said inclination being formed by twisting said leaf spring member at said latch portion thereof, said front plate having a cutout portion of a size slightly larger than said latch portion through which said latch portion projects, an actuating member for positively moving said main portion from a closing position of said latch portion to an opening position thereof, and for releasing said main portion so as to enable movement of said latch portion to the closing position by the resilience of said spring member.

5. A door lock comprising a support including a front plate, a leaf spring member mounted on the inside and near one end of said front plate and having a main portion adapted for resilient movement relative to said end, said main portion including a latch portion adapted to lock the door, said latch portion having an inclination extending transversely to the length of said leaf spring member and overhanging one end of said member, said inclination being formed by twisting said leaf spring member at said latch portion thereof, said front plate having a cutout portion of a size slightly larger than said latch portion through which said latch portion projects, an actuating member disposed adjacent said one end for positively moving said one end and thereby moving said main portion from a closing position of said latch portion to an opening position thereof, and for releasing

said main portion so as to enable movement of said latch portion to the closing position by the resilience of said spring member.

5. A door lock comprising a support including a front plate, a leaf spring member mounted on the inside and near one end of said front plate and having a main portion integral therewith adapted for resilient movement relative to said end, said main portion including a bent portion forming a latch portion adapted to lock the door, said front plate having a cutout portion forming an aperture of a size slightly larger than said latch portion through which said latch portion projects, an actuating member for positively moving said main portion from a closing position of said latch portion to an opening position thereof, and for releasing said main portion so as to enable movement of said latch portion to the closing position by the resilience of said leaf spring member, said support comprising a housing, one end of said leaf spring member being mounted within said housing on said inside and near said one end of said front plate containing said aperture and at a point spaced from said aperture, said spring member extending in a longitudinal direction along said front plate and over and beyond said aperture, said actuating member being disposed within said housing at the side opposite to the mounting of said leaf spring member so as to cooperate with the other end of said spring member.

10. A door lock comprising a support including a front plate, a leaf spring member mounted on the inside and near one end of said front plate and having a main portion adapted for resilient movement relative to said end, said main portion including a latch portion adapted to lock the door, said latch portion being inclined transversely to the length of said leaf spring member, said inclination being formed by twisting said leaf spring member at said latch portion thereof, said front plate having a cutout portion of a size slightly larger than said latch portion through which said latch portion projects, an actuating member for positively moving said main portion from a closing position of said latch portion to an opening position thereof, and for releasing said main portion so as to enable movement of said latch portion to the closing position by the resilience of said spring member.

15. A door lock as defined in claim 6, wherein said other end of said spring member as seen from its mounted end is bent inwardly into said housing from a point adjacent to the remote edge of said aperture, and is then bent back in the direction to said front plate of said housing, said actuating member being disposed at a point intermediate the last-mentioned bent portion of said spring member and said front plate of said housing.
